UNITED STATES PATENT OFFICE.

ISAAC DAVIDSON, OF ALBERT LEA, MINNESOTA.

COUPLING-BOLT.

1,225,932.

Specification of Letters Patent.

Patented May 15, 1917.

Application filed April 21, 1916. Serial No. 92,729.

To all whom it may concern:

Be it known that I, ISAAC DAVIDSON, a citizen of the United States, residing at Albert Lea, in the county of Freeborn, State of Minnesota, have invented certain new and useful Improvements in Coupling-Bolts; and I do hereby declare the following to be a full, clear, and exact description of the invention, such as will enable others skilled in the art to which it appertains to make and use the same.

This invention relates to coupling bolts.

The object of the invention is to provide a coupling bolt embodying an improved construction whereby desired members may be coupled and uncoupled with ease and facility, said bolt being particularly adapted for coupling a windmill rod and a pump rod.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a view in elevation of the improved coupling bolt;

Fig. 2, a similar view taken at right angles to what is shown in Fig. 1;

Fig. 3, a section on the line 3—3 of Fig. 1, and

Fig. 4, a view in elevation showing a windmill rod and pump rod coupled through the medium of the bolt.

Referring to the drawings the improved bolt is shown as comprising a shank body 10 one end of which terminates in an eye 11 to form a hand piece for convenience in manipulating the same. The end of the body remote from the body 11 is cut away to form a reduced portion 12 having a flat face 13 and to form a shoulder 14. Secured against the flat face 13 is a leaf spring catch 15. This catch is inclined outwardly

in the direction of the shoulder 14 and the free end thereof is curved inwardly as at 16, the outer terminal of this curved portion 16 being always disposed within the limits of the shoulder 14.

From the construction just described it will be obvious that if the bolt is inserted through registering openings of members to be coupled the catch 15 will be forced inwardly owing to its inclination until the shoulder 14 is disposed beyond the opening 16 in the adjacent member to be coupled when said catch will spring outwardly to the position shown in Fig. 2 and act as a stop to prevent the bolt from becoming accidentally displaced. To remove the bolt it is only necessary to pull the same longitudinally in the direction of the eye 11 with sufficient force to cause one of the coupled members to act upon the curved free end of the catch to force the latter inwardly. In other words the catch 15 does not have to be manually operated either in coupling or uncoupling.

What is claimed is:—

A coupling bolt comprising an integral straight body having one end portion reduced in one direction diametrically of the body with a resultant shoulder, a leaf spring riveted against the outer end portion of the face of the reduced portion and having its butt extended against and across the adjacent end face of the body, said leaf spring extending divergently from the face of the reduced portion to a point beyond the face of the unreduced portion and short of said shoulder and then extending to a point behind said shoulder, whereby the leaf spring will be held against pivotal movement on its rivet and the bolt may be seated by hammer blows against the opposite end of the integral body member.

In testimony whereof, I affix my signature, in the presence of two witnesses.

ISAAC DAVIDSON.
